UNITED STATES PATENT OFFICE.

EDWIN M. BAKER, OF ANN ARBOR, MICHIGAN, ASSIGNOR TO CHRISTIAN GIRL, OF KALAMAZOO, MICHIGAN.

METHOD OF DETERMINING BORIC ACID IN NICKEL-CONTAINING SOLUTIONS.

No Drawing.

Application filed January 24, 1923. Serial No. 614,685.

To all whom it may concern:

Be it known that I, EDWIN M. BAKER, a citizen of the United States, residing at Ann Arbor, in the county of Washtenaw and State of Michigan, have invented a certain new and useful Improvement in Methods of Determining Boric Acid in Nickel-Containing Solutions, of which the following is a full, clear, and exact description.

10 This invention relates to a method of determining the quantity or percentage of boric acid in a nickel-plating solution. In practicing the nickel-plating of various articles, it has been found to be desirable, if 15 not necessary, to include a certain proportion of boric acid in the electro-plating solution. For instance, a solution such as has been employed by me with satisfactory results contains, for each gallon of solution:—

20 2 ounces of boric acid (H_3BO_3).
32 ounces of nickel sulphate ($NiSO_4 \cdot 7H_2O$).
3.3 ounces of nickel chloride ($NiCl_2 \cdot 6H_2O$).

25 The determination, by titration, of the boric acid content in such nickel-containing solutions has been practically impossible with indicators in use heretofore. The presence of the nickel in the solution has resulted in 30 the precipitation of the nickel before the occurrence of the color-reaction which indicates when the boric acid is neutralized by the standard alkali, with the result that the boric acid content, as indicated, is in excess 35 of that actually present. It has been proposed to remedy this inaccuracy by removing the nickel prior to the addition of the standard alkali; this, however, requires so much time and expense as to render determination by this method impracticable for 40 controlling the composition of commercial nickel plating baths.

By virtue of my invention, I am enabled 45 to determine accurately the boric acid present in nickel-containing solutions without the necessity for precipitating the nickel and, in fact, irrespective of the presence of nickel therein.

50 In practicing my invention, a measured volume or unit of nickel-plating solution is taken. To this is added a few drops of an acid indicator, known as methyl-orange,

which imparts a distinctive yellowish color to the sample of the solution. A standard acid (sulphuric) is then added to the solution until its color changes to red, or reddish-orange. The purpose of adding the acid is to convert any borates that may be present into boric acid; and the change in color to red or reddish-orange occurs when 60 this conversion is completed and without the necessity for the use of an excess of the standard acid, so that the only free acid within the sample of the solution will then be boric acid. To prevent dissociation of 65 the alkali borate or borates which are to be formed hereafter, I then add glycerol or mannit to the solution. I then add a few drops of an indicator which is composed of bromo-cresol purple (dibromo-o-cresol sulfon phthalein) and bromo-thymol blue (dibromo thymol sulfon phthalein), preferably 70 in the proportions of five parts of the former to one part of the latter. An important feature of my invention is that this indicator will give a distinctive color at the moment when a standard alkali (such as 75 $NaOH$) has been added in just sufficient quantity (with agitation) to neutralize the acid, converting the boric acid into the appropriate alkali borate. This color-change 80 (which is from green to blue) will occur at a time when this standard alkali has been added in such quantity that substantially one molecule of such alkali will have been 85 added to the sample of solution for each molecule of boric acid contained therein. The color-change referred to will occur 90 when the acidity changes from $pH=5$ to $pH=6$. The amount of alkali necessary to be added to bring about this color change will be just sufficient to neutralize the boric acid but will be insufficient to cause the precipitation of any nickel which may be present in the solution. That is to say, the indicator will perform its function of showing 95 the moment when the acid is neutralized, irrespective of the presence or absence of nickel in the solution.

I am aware of the fact that it has been 100 proposed to determine the quantity of boric acid in a solution containing only chlorides or other salts of the alkalis or other non-interfering bases and that, in such deter-

mination, the solution has been treated with methyl-orange and glycerol or mannit. However, the indicator employed thereafter (phenolphthalein) has been of such a character that, if any nickel salts be present, all or part of the nickel would have to be precipitated (as a hydrated form of nickel oxide) before a distinctive color-change could be produced in the indicator. This method is impractical for use in connection with a nickel-plating solution, for reasons set forth hereinbefore.

Having thus described my invention, what I claim is:

- 15 1. The method of determining boric acid present in a nickel-containing solution, said method comprising the addition, to a measured volume of said solution, of a standard acid in sufficient quantity to convert any borates that may be present into boric acid; then adding to the solution an agent capable of preventing the dissociation of the alkali borate or borates to be formed thereafter; then adding to such solution an indicator operative within limits of acidity from pH=5 to pH=6 to impart a characteristic color to the solution immediately upon the neutralization of the boric acid; and then adding to the solution a standard alkali, 25 with agitation, until such characteristic color is obtained.
- 20 2. The method of determining boric acid present in a nickel-containing solution, said method comprising the addition, to a measured volume of said solution, of a standard acid in sufficient quantity to convert any borates that may be present into boric acid; then adding to the solution an agent capable of preventing the dissociation of the alkali 25 to be formed thereafter; then adding to such solution an indicator consisting of bromo-cresol purple and bromo-thymol blue; and finally adding to the solution a standard alkali, with agitation, until a characteristic 40 color is obtained.
- 25 3. The method of determining boric acid in a nickel-containing solution which comprises titrating the solution with a standard acid, in the presence of an indicator operative within limits of acidity from pH=5 to pH=6, until a characteristic change of color is imparted to such solution; and then titrating the solution with a standard alkali, in the presence of glycerol or mannit and in the presence of an indicator capable of imparting a characteristic color to the solution upon the neutralization of the acid and irrespective of the presence of nickel or nickel salts in the solution.
- 30 4. The method of determining boric acid in a nickel-containing solution which comprises titrating the solution with a standard acid, in the presence of an indicator, until a characteristic change of color is imparted to such solution; and then titrating the solu-

tion with a standard alkali, in the presence of glycerol or mannit, and with an indicator comprising a mixture of bromo-cresol purple and bromo-thymol blue.

5. The process of determining boric acid 70 in a nickel-containing solution which comprises titrating the solution with a standard alkali in the presence of mannit or glycerol and with the employment of an indicator composed of approximately five parts of 75 bromo-cresol purple to one part of bromo-thymol blue.

6. The process of determining boric acid 80 in a nickel-containing solution which comprises titrating the acidified solution with a standard alkali in the presence of mannit or glycerol and with the employment of an indicator composed of bromo-cresol purple and bromo-thymol blue in proportions to produce a characteristic color-change immediately upon the neutralization of the boric acid.

7. The process of determining boric acid 90 in a nickel-containing solution which comprises titrating the solution with a standard alkali in the presence of mannit or glycerol and with the employment of an indicator composed of bromo-cresol purple and bromo-thymol blue in such proportions as will produce a sharp color-change at the time when 95 one molecule of the alkali has been added for each molecule of boric acid present in the solution at the time of beginning the addition of alkali.

8. In the determination of boric acid in a 100 nickel-containing solution, the employment of an indicator operative within limits of acidity from pH=5 to pH=6 to give a sharp or characteristic change of color as soon as all of the boric acid has been neutralized or reacted upon by a standard alkali and before sufficient alkali has been added to react additionally with any nickel salt.

9. In the determination of boric acid in a 110 nickel-containing solution, the employment of bromo-cresol purple and bromo-thymol blue in such relative proportions as will give a sharp or characteristic change of color as soon as all of the boric acid has been neutralized or reacted upon by a standard alkali 115 and before sufficient alkali has been added to react additionally with any nickel salt.

10. The method of determining boric acid 120 in a nickel-containing solution having all of the borate content in the form of boric acid and containing also an excess of other acid or acids, said method comprising titrating the solution with a standard alkali, in the presence of an indicator operative within limits of acidity from pH=5 to pH=6 to 125 impart a characteristic color to the solution immediately upon the neutralization of the boric acid.

11. A mixture of bromo-cresol purple with 130 bromo-thymol blue in proportions suitable

to form an indicator capable of undergoing lution of bromo-thymol blue in substantially a sharp change in color immediately upon the proportions of five parts of the former neutralization by a standard alkali of the solution to one part of the latter solution. boric acid in a nickel-containing solution. In testimony whereof, I hereunto affix my

- 5 12. An indicator comprising a mixture of a solution of bromo-cresol purple with a so-
